FILLING MACHINE HAVING RETICULATED DRUMS FOR FILLING FABRIC CONTAINERS WITH FIBROUS MATERIAL

Max Goldberg, New York, N. Y.

Application August 9, 1945, Serial No. 609,745

2 Claims. (Cl. 226—19)

1

This invention relates to a filling machine for filling containers with fibrous filling material particularly of the very air buoyant type, such as the downy covering of cattails, known in the art as Typha. Also for such filling materials as kapok, down and the like, and particularly into non-porous containers.

An object of this invention is to provide a filling machine in which containers are filled with material which is so light as to practically float in the air.

Another object of this invention is to provide a filling machine having two co-acting perforated drums mounted to rotate toward each other within openings in the side walls of a hopper, and feed fibrous filling material from the hopper through a nozzle and into a container to be filled.

Another object of this invention is to provide suction means connected with suction chambers fixed inside the perforated drums through which the air entrained between the interstices of the fibrous material is removed therefrom while the drums exert a feeding action on the fibrous material.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a top plan view of the two-drum filling machine.

Figure 2 is a cross-sectional view, the section being taken as on line 2—2 in Figure 3.

Figure 3 is a view showing a front elevation of the filling machine, partly broken away to show the interior of the drums.

Figure 4 is an end view of the filling machine.

Figure 5 is a front elevation of the filling machine showing drive mechanism.

Figure 6 shows a fragmentary portion of the filling machine taken along the outer surface of the front wall of the casing, the front wall being broken away to show a semi-circular gasket.

In the illustrated embodiment of the invention, the numeral 10 indicates a filling machine for filling containers such as cushions, pillows, etc., with material which is so light as to practically float in the air.

The filling machine 10 comprises a casing 11

which is substantially funnel-shaped. Rotatably mounted in bearings 12, 12 at the front wall 13 of the casing 11 are two shafts 14, 14 with their axes in a horizontal plane. The shafts extend into the casing 11 and have drums 15, 15 secured at their ends inside the casing. The casing 11 has side openings 16, 16 in opposite side walls through which portions of the drums extend outwardly.

Gears 17, 17 are fixed to the shafts 14, 14 and are in intermeshing relation. A pinion gear 18 carried by a motor 20 is in intermeshing relation with one of the gears 17 and when the motor shaft rotates, the drums 15 rotate towards each other.

For the purpose of this invention, the drums 15 have small apertures 19 all around their circumferences. The casing 11 has an inlet or hopper portion 11' for filling material at its upper end. The casing has a nozzle or outlet 22 at its lower end.

The drums are in slightly spaced-apart relation and provide a passageway 23 from the inlet of the hopper 11' to the outlet 22.

Suction housings or chambers 25 are fixedly secured inside the rotatable drums 15. Each suction chamber has an open arcuately shaped side adjoining the inner periphery of a drum. Suction means such as an air blower 26 is in communication with the suction chambers 25, by means of a pipe 24.

It is to be noted that the filling material has interstices between the fibers, and when deposited in the inlet or hopper portion 11' of the casing 11 is fed by the drums 15 into and through the nozzle 22 and into a container 28 suitably held by the nozzle. The air displaced by the filling material from the container 28 is removed by the suction means 26. The air passes outwardly from the container through the interstices between the fibers in the nozzle. The direction of flow of the air is opposite to the direction of feeding of the filling material through the nozzle 22.

Tractive driving force between the fibrous material and the peripheral surfaces of the drums 15 is imparted to the fibers by the suction through the apertures 19 in the drums 15 which form nodules of fibrous material in each perforation.

At the greatest compression point 30, or the point where the two drums are nearest, the filling material is compressed and acquires its greatest tractive driving force to deliver the material into and through the nozzle.

At a lower clearance point 31 where the nozzle

walls adjoin the revolving drums there are sealing strips 32 which are fixed to edges of the suction chambers 25 and frictionally contact the inner peripheral surfaces of the revolving drums 15.

The compressed material passes the point of greatest compression 30, breaks up into batches, and continues this motion for a short distance due to the influence of the suction through the apertures 19. Sealing strips 33 fixed to the upper edge portions of the nozzle 22 compensate for mechanical clearances and prevent air at atmospheric pressure from leaking into the sub-atmospheric nozzle chamber.

The adhering filling material on the drums, after passing the lower edges of the walls of the suction chambers, is past the influence of the suction in the suction chambers through the perforations and is released from contact with the apertured drums and is forced downward by the compressed material at the point of greatest compression 30 directly into and through the outlet 22.

As shown in Figures 1 and 6, a substantially semi-circular gasket 35 fits between the drum 15 and the casing 11 and prevents leakage around the drums. The gasket is held in any suitable manner in fixed relation to the casing. Four gaskets are employed, one gasket at each end face of the drums.

Each drum 15 has an annular flange 29 at the end opposite the solid end wall 34. Each flange 29 is in frictional engagement with a gasket 35 on the side of the casing 11 facing the suction means 26. A flanged sleeve 36 is fixed to the wall 34 by rivets 37. A pin 38 secures the shaft 14 to the flanged sleeve 36.

As shown in Figure 2, a branch pipe 24' is suitably connected to the suction housing 25 by a flange 27. Each of the suction housings 25 has a flange for connection with the branch pipe 24'. It is to be noted that the suction chambers 25 are secured to the pipes 24'.

In accordance with the patent statutes I have described and illustrated the preferred embodiment of my invention, but it will be understood that various changes and modifications can be made therein without departing from the spirit of the invention as defined by the appended claims.

I claim:

1. In a filling machine for filling containers with substantially air buoyant material, comprising a casing, two perforated drums rotatably mounted in said casing with their axes lying in a single horizontal plane, means for rotating said drums toward each other, said casing having a hopper portion or inlet at its upper end and a nozzle at its lower end, said drums being slightly spaced apart and providing a passageway therebetween from said hopper to said nozzle, suction chambers fixedly secured inside said rotatable drums, each suction chamber having an arcuately-shaped open side adjoining the inner periph-

ery of a drum, suction means in communication with said suction chambers and with said filling material in said casing through said perforations, whereby fibrous material having interstices and deposited in said hopper is fed by said drums into and through said nozzle while the entrained air is removed from said filling material through said interstices, the direction of the flow of said entrained air being opposite to the direction of feeding of said filling material into said nozzle, said nozzle being under sub-atmospheric pressure, and sealing strips fixed to edges of said suction chambers and frictionally contacting said drums to prevent air under atmospheric pressure from leaking into said nozzle.

2. In a filling machine for filling containers with substantially air buoyant material, comprising a casing, two perforated drums rotatably mounted in said casing with their axes lying in a single horizontal plane, means for rotating said drums toward each other, said casing having a hopper portion or inlet at its upper end and a nozzle at its lower end, said drums being slightly spaced apart and providing a passageway therebetween from said hopper to said nozzle, suction chambers fixedly secured inside said rotatable drums, each suction chamber having an arcuately-shaped open side adjoining the inner periphery of a drum, suction means in communication with said suction chambers and with said filling material in said casing through said perforations, whereby fibrous material having interstices between the fibers and deposited in said hopper is fed by said drums into and through said nozzle while the entrained air is removed from said filling material through said interstices, the direction of the flow of said entrained air being opposite to the direction of feeding of said filling material into said nozzle, said nozzle being under sub-atmospheric pressure, and sealing strips fixed to edges of said suction chambers and frictionally contacting said drums to prevent air under atmospheric pressure from leaking into said nozzle, said suction chambers having walls positioned substantially radially of said drums, the distance between said radial walls being less than the distance between said sealing strips.

MAX GOLDBERG.
